AUTOMOBILE DOOR OR BODY AND WINDOW
CONSTRUCTIONThomas W. Holt and John F. Levan, Elkhart,
Ind., assignors to Excel Curtain Company, Elkhart, Ind., a corporation of Delaware

Application January 21, 1932, Serial No. 587,948

7 Claims. (Cl. 296—48)

This invention relates to windows such as the windows of automobiles which are capable of being raised and lowered and which are supported within the automobile body below the belt or within the door body; and it has for its object a particularly simple, efficient and compact means for supporting the window sash and holding it from looseness and rattling when in both its open and closed position, and for so supporting the sash that it can be raised and lowered with lifting mechanism without binding due to edgewise thrust of the sash, particularly if the lifting force is applied unevenly or more toward one side of the sash than the other. Another object is a particularly simple and efficient sash guide means.

The invention consists in the novel features and in the combinations and constructions hereinafter set forth and claimed.

In describing this invention, reference is had to the accompanying drawings in which like characters designate corresponding parts in all the views.

Figure 1 is a fragmentary elevation, partly broken away, of an automobile door to which our invention is applied.

Figure 2 is a sectional view on line 2—2, Figure 1.

Figure 3 is an enlarged detail view of the carriage for the sash, the contiguous portion of the sash being shown and the contiguous portion of the guide being shown in section.

Figures 4 and 5 are sectional views taken respectively on lines 4—4 and 5—5, Figure 3.

Figure 6 is an enlarged sectional view on lines 6—6, Figure 1.

Figure 7 is a fragmentary vertical sectional view of another form of one of the guides at the edge of the sash with one of the tail pieces therein.

Figure 8 is an enlarged sectional view on line 8—8, Figure 7.

1 designates the supporting body here illustrated as the hollow body of an automobile door. 2 designates the sash, which preferably has a marginal frame consisting of top and bottom rails 3 and 4 and stiles 5. The sash is guided by means located wholly within the door body 1, and this means includes a guide located in the door body between the vertical lines of the stiles 5 and preferably about midway between such lines. The sash is provided with a carriage depending from the intermediate part of its bottom rail and movable along the guide, the carriage being offset from the plane of the sash or out

of the path of the sash, as seen in Figures 2 and 4. The carriage and the guide are provided with coacting means for holding the sash from edgewise movement and also from movement in a direction at an angle to the plane of the sash. 5 6 designates the guide which is here shown as in the form of opposing channels, these channels being formed up from the opposite marginal portions of a base 7. The guide is secured in the door in any suitable manner, it being generally 10 secured to cross frame members 8 by screws 9 passing through the base 7.

10 designates the carriage which depends from the bottom rail 4 of the sash. It is connected to the bottom rail by a curved bracket 11 so that the carriage is offset from the plane of the sash. 15 The side margins of the carriage extend into the channels and are provided with anti-friction means as a pair of spaced apart rollers 12 at each side edge. Each roller is mounted on a 20 stud 13 and has anti-friction bearings 14 on the stud. The ends of the studs slidably engage like side walls of the channel and the margins of the carriage slidably engage the other side walls 25 of the channels so that by reason of this engagement the sash is held from vibrating in a direction at an angle to its plane. One pair of rollers run on the bottom of one channel and the other pair along a spring pressed track 15 extending substantially parallel to the bottom of the 30 other channel. The spring pressed track provides means for holding the sash from edgewise movement or vibration.

Usually in sashes used in automobile construction, the sashes are guided wholly at their side 35 margins or by vertical extensions as 20 of the stiles running in channels or along guides as 21 within the door or automobile body. As shown in Figures 2 and 6, each of the channels or guides 21 is provided with a spring pressed 40 track 17 along one side thereof and the extensions 20 are provided with projections 22 on opposite sides thereof, the projections on one side slidably engaging the track and those on the other side, the side wall of the channel opposed 45 to the track. Each extension is preferably a channel and the projections are struck from the side flanges of the channel and are in the form of straps formed by slitting the side wall of the channel and then bulging the straps outward, leaving their ends joined to the side wall. The extensions 20 serve to firmly support the sash when closed. However, edgewise movement or play is prevented by the guide 6 and carriage 10. 50 As seen in Figures 7 and 8, the guides 21 may 55

be unprovided with the spring pressed tracks and the extensions 20 of the stiles provided with spring pressed shoes thrusting against the inner faces of the side walls of the channels 21. The shoes 5 are preferably arranged in pairs spaced apart along the extension 20. 30 designates the shoes pressed by springs 31 located in the channel of the extensions and arranged to press the shoes outward, the shoes being interlocked with the extensions to hold them from displacement. As 10 shown, the shoes consist of a base plate 32 on the inner side of the channel and having a projection 33 extending through a hole 34 in the side flange of the channel of the extension so as to engage the side flanges of the channel shaped guide 21. The shoes are fibre faced and preferably the entire shoe is a fibre block. The 15 springs 31 are coiled springs and each seats at one end around a projection 35. The projection 20 35 is here shown as a pin having a collar 36 thrusting against the inner face of the side flange of the guide 21 and having a guide pin 37 extending in a perforation in said side flange. The 25 projections 35 holds the springs from displacement. This construction of guide means for the sash is especially simple, practical and economical.

The lifting mechanism usually consists of an arm or a pair of arms 38 operated by a suitable 30 crank 39, the arms having rollers which work in a transverse groove 40 formed along the bottom rail. The resultant of the lifting forces of the two arms is not always parallel to the guide and hence, the sash is subject to an edgewise thrust 35 which causes it to bind more or less, and when but one lift arm is used, the binding effect is more pronounced. By our invention not only is the binding effect eliminated but the sash is held against misalignment, either when the lifting 40 force is applied directly to the bottom rail of the sash or to the carriage.

What we claim is:

1. The combination of a supporting body, a 45 sash movable into and out of the body, the body being provided with a guide located between the vertical lines of the side edges of the sash and out of the plane of the sash, and the sash having an elongated carriage extending below its bottom rail in offset relation to the plane of the 50 sash and extending below the lowermost edge of the sash structure, and movable along the guide and coacting with the guide near the upper and lower ends thereof and thereby serving as a brace to hold the sash from edgewise movement, the carriage being formed with antifriction 55 means coacting with the guide and spring pressed means for holding the carriage in snug engagement with the guide.

2. The combination of a supporting body, a 60 sash movable into and out of the body, the body being provided with a guide located between the vertical lines of the side edges of the sash and out of the plane of the sash, and the sash having an elongated carriage extending below its bottom rail and offset from the plane of the sash and movable along the guide, said guide including 65 opposing channels facing each other and the carriage having its margins movable in the channels, one of the channels being provided with a spring pressed track pressing edgewise on the carriage.

3. The combination of a supporting body, a

sash movable into and out of the body, the body being provided with a guide located between the vertical lines of the side edges of the sash and out of the plane of the sash, and the sash having an elongated carriage extending below its bottom rail and offset from the plane of the sash and movable along the guide, the carriage being formed with antifriction means coacting with the guide and spring pressed means for holding the carriage in snug engagement with the guide, said 5 guide including opposing channels facing each other and the carriage having its margins movable in the channels, one of the channels being provided with a spring pressed track pressing edgewise on the carriage. 10

4. The combination of a supporting body, a sash movable into and out of the body and having a bottom rail, the body being provided with a guide located between the vertical lines of the side edges of the sash and out of the plane of the sash, and the sash having an elongated carriage extending below its bottom rail and offset from the plane of the sash and movable along the guide, the guide including 20 opposing channels facing each other and the carriage having its margins extending into the channels and slidably fitting the opposing sides of the channels, and means in one of the channels for pressing the carriage edgewise. 25

5. The combination of a supporting body, a sash movable into and out of the body, the body being provided with a guide located between the vertical lines of the side edges of the sash and out of the plane of the sash, and the sash having an elongated carriage extending below its bottom rail and offset from the plane of the sash and movable along the guide, the guide including 30 opposing channels facing each other and the carriage having its side margins extending into the channels and slidably fitting the opposing sides of the channel, one of the channels being formed with a spring pressed track extending substantially parallel to the bottom of the channel and the carriage having spaced apart rollers movable along the bottom of one channel and 35 along said track in the other channel.

6. The combination of a supporting body and a sash movable into and out of the body, the sash having a rigid rail along the lower edge thereof in which the lower margin of the glass 50 pane is mounted, the body being provided with a guide located between the vertical lines of the side edges of the sash and out of the plane of the sash, and the sash having an elongated carriage extending below its bottom rail in offset relation 55 to the plane of the sash and movable along the guide and coacting with the guide to hold the sash against lateral edgewise movement and movement at an angle to the plane of the sash and spring means for holding the carriage from 60 tilting movement relatively to the guide.

7. A window assembly comprising in combination a window adapted to reciprocate into and out of a window well, guideways contacting solely with the inner and outer faces of the window for 65 guiding the window when it is reciprocated, and guide means positioned within the window well for rigidly guiding the window against edgewise movement in its own plane when the window is reciprocated into and out of the window well. 70
